[57] **CLAIM**

The ornamental design for a combined dental flosser and toothpick, as shown and described.

DESCRIPTION

FIG. 1 is a top plan view of a representative embodiment of our new design concept for combined dental flosser and toothpick, the bottom plan view (not shown) being a mirror image thereof.

FIG. 2 is a frontal elevational view, as seen along the direction of line 2—2 of FIG. 1;

FIG. 3 is a rearward elevational view, as seen along the direction of line 3—3 of FIG. 1;

FIG. 4 is a right-side elevational view, as seen along the direction of line 4—4 of FIG. 1;

FIG. 5 is a left-side elevational view, as seen along the direction of line 5—5 of FIG. 1; and,

FIG. 6 is a top and side perspective view thereof.

FIG. 5FIG. 4FIG. 1FIG. 3FIG. 2FIG. 6
